CLAIM

The ornamental design for an electronic controller for
aviation refueler, as shown and described.

DESCRIPTION

FIG. 1 is a top, front and side perspective view of an
electronic controller for aviation refueler showing my
new design.

FIG. 2 is a front elevational view thereof;

FIG. 3 is a top plan view thereof;

FIG. 4 is a bottom plan view thereof;

FIG. 5 is a left end elevational view thereof; and

FIG. 6 is a right end elevational view thereof.

Fig. 3.

Fig. 4.

Fig. 5.

Fig. 6.

Fig. 1.

Fig. 2.
